ROTARY WEB PRINTING PRESS

Howard M. Barber, Pawcatuck, Conn., assignor
to C. B. Cottrell & Sons Company, Westerly,
R. I., a corporation of Delaware

Application June 6, 1939, Serial No. 277,570

2 Claims. (CL 101—179)

In high speed rotary web presses where quick drying inks are used in the printing units it is usual to provide drying units to dry the freshly printed web after it leaves the printing units.

5 These drying units usually dry the ink by evaporation and, in any event, through the application to the web of a considerable degree of heat by means of gas burners, steam drums, or the like, in combination with a cooling means. Under 10 this treatment the web has a tendency to shrink so that due to the increase in tension there is less paper being presented to the second printing unit than was presented to the first printing unit. Therefore, if the corresponding form and impres- 15 sion cylinders of the printing units are made exactly the same size and the plates and make-ready bear the same relation to the bearers of the respective cylinders, the web will either break or run under such extreme tension that it will 20 wrinkle badly and otherwise interfere with the color register in the second printing unit.

The object of my invention is to provide accurate register in a rotary web printing press in the second printing unit, said unit comprising an 25 impression cylinder and form cylinders therefor, the diameters of said cylinders being slightly less than the diameters of the corresponding cylinders of the first printing unit.

A practical embodiment of my invention is 30 represented in the accompanying drawing which is a diagrammatic representation of a side elevation of so much of a printing press as will give an understanding of my invention.

In the form shown, the first printing unit is 35 represented as a five color unit, the impression cylinder being denoted by 1 and its five form cylinders by 2, 3, 4, 5 and 6. Inking mechanisms for the form cylinders are denoted by 2^a, 3^a, 4^a, 5^a and 6^a, and apply the ink to their respective form cylinders in the usual manner.

The second printing unit for perfecting the web is herein represented as a five color unit, the impression cylinder being denoted by 7 and its five form cylinders by 8, 9, 10, 11 and 12; the diameters of the impression and form cylinders of this 45 second printing unit are slightly less than the diameters of the corresponding cylinders of the first printing unit. The inking mechanisms for the form cylinders of the second printing unit are denoted by 8^a, 9^a, 10^a, 11^a and 12^a, and apply the ink to their respective form cylinders in the usual manner.

The first drying unit is herein represented as comprising a heating unit 13, such as a gas burner 50 and two cooling cylinders 14 and 15.

The second drying unit is herein represented as comprising a heating unit 16, such as a gas burner and two cooling cylinders 17 and 18.

These two drying units are provided with shields 19 and 20 in order that the vapors arising from drying the web may be easily disposed of and dissipated by blower or suction devices 21, 22 so that the vapors will not again come in contact with the printed surface of the web.

Any heating medium, such as gas, may be applied to the heating units 13, 16, and any suitable cooling medium, such as cold water, may be supplied to cooling cylinders 14, 15 and 17, 18.

The web may be fed from the supply roll 23 in any well known or approved manner.

In operation, the web is led from the supply roll to and through the first printing unit where it is printed in multicolor on the first side thereof, then to and through the heating unit 13 and around the cooling cylinders 14, 15 of the first 20 drying unit. From thence the web is led to and through the second printing unit where it is printed in multicolor on the second side thereof, then to and through the heating unit 16 and around the cooling cylinders 17, 18 of the second 25 printing unit. The perfected web may then pass in any desired direction to a delivery point.

The means for driving the several units is not shown or described herein but any well known or approved means may be used. It will be understood that either of the units may be driven separately either for the purpose of "making-ready" or for any other purpose.

It is to be understood that guide rolls are provided for passing the web from the supply roll in 35 prescribed paths to and through the several units and to a predetermined delivery point.

While I have shown and described five form cylinders for each printing unit, it is evident that if so desired, one or more of the form cylinders 40 may be silenced in the usual manner.

Also, while I have shown drying units for each printing unit it is obvious that the second drying unit may be eliminated if so desired.

It is to be understood that any well known or 45 approved quick drying inks may be used in the printing press.

From the above description it will be seen that I have provided not only a simple but effective means whereby register may be effected in the 50 second printing unit with a minimum of effort by making the cylinders thereof slightly smaller than the corresponding cylinders of the first printing unit.

It is evident that various changes may be re- 55

sorted to in the construction, form and arrangement of the several parts without departing from the spirit and scope of my invention, and hence I do not intend to be limited to the particular embodiment herein shown and described, but

5 What I claim is:

1. In a rotary web printing press, first and second printing units, each printing unit comprising an impression cylinder and form cylinders, and 10 means for drying the web after it leaves the first printing unit, the diameters of the impression and form cylinders of the second printing unit being slightly less than the diameters of the

corresponding impression and form cylinders of the first printing unit.

2. In a rotary web printing press, first and second printing units, each printing unit comprising an impression cylinder and form cylinders, means 5 for drying the web after it leaves both the first and second printing units, the diameters of the impression and form cylinders of the second printing unit being slightly less than the diameters of the corresponding impression and form 10 cylinders of the first printing unit.

HOWARD M. BARBER.
